UNITED STATES PATENT OFFICE.

WILLIAM S. GUINTER, OF ROCKFORD, ILLINOIS.

FENCE-MAKING TOOL.

No. 913,725.

Specification of Letters Patent.

Patented March 2, 1909.

Application filed January 4, 1908. Serial No. 409,330.

To all whom it may concern:

Be it known that I, WILLIAM S. GUINTER, a citizen of the United States, residing at Rockford, in the county of Winnebago and State of Illinois, have invented a new and useful Fence-Making Tool, of which the following is a specification.

This invention relates to fence making tools.

10 The object of the invention is to provide a tool of this character which shall, in a novel and practical manner, combine the features of a wire cutter, wire splicer, staple and nail puller, the various parts of the tool being so disposed relatively to each other that in use one will not interfere with the other.

20 With the above and other objects in view, as will appear as the nature of the invention is better understood, the same consists in the novel construction and combination of parts of a fence making tool, as will be herein-after fully described and claimed.

25 In the accompanying drawing forming a part of this specification, and in which like characters of reference indicate corresponding parts, Figure 1 is a perspective view of the tool as it appears when employed as a wire cutter. Fig. 2 is a view in elevation of the combined wire splicer and wire cutter removed from the hammer. Fig. 3 is a transverse sectional view through the claw of the hammer taken on the line 3—3 of Fig. 1. Fig. 4 is a longitudinal sectional view taken on the line 4—4 of Fig. 1, the combined wire splicer and wire cutter being removed.

30 The implement embodies a hammer head 1 provided with a claw 2, a handle or helve 3, and a combined wire cutter and splicer, designated generally 4. The poll 5 of the hammer is extended outward beyond the eye to form two parallel flanges 6 each of which is provided with a notch or seat 7 and 8, respectively, in which the wire to be severed is held. The walls of the notch 7 are parallel with each other, while the walls of the notch 8 are oppositely inclined to provide double cutting edges, as will readily be understood by reference to Fig. 1. The members of the claw 2 are herein shown as having their outer faces flat, and the slot of the claw from its crotch outward for any desired distance is provided with oppositely beveled inwardly projecting ribs 9 that are adapted to fit under the head of a nail and

thus insure its positive extraction. The terminal portions of the claw constitute staple pullers, and for this purpose are only slightly curved and are pointed, so that should the staple to be extracted lie close to the post, the pointed terminals of the claw may readily be worked thereunder.

35 The combined splicer and nail cutter shown in Fig. 2 comprises a handle or lever 10 and a head 11, the latter being approximately circular in shape. The head is provided in its interior with a keyhole-shaped slot 12, and in its periphery with a notch 13 having oppositely inclined cutting edges 14 and with a curved notch or slot 15 the end wall of which is disposed approximately opposite the like wall of the notch 13. As will be seen by reference to Fig. 2, the eye of the slot 12 is eccentrically disposed relatively of the head, so that when the attachment is combined with a stud 15^x projecting from one side of the poll, the stud will occupy a position approximately at the center of the head. This stud may be secured to the poll in any preferred manner, preferably by a threaded connection, so that in the event of breakage, it may readily be replaced. By the employment of the keyhole slot 12, the implement 4 can be readily connected with and disconnected from the hammer poll, according to the character of work that is to be done.

40 When used as a wire cutter, the wire is positioned in the notches 7 and 8 of the hammer head, and in the notch 13 of the implement 4, and upon the latter being turned upon the stud 15^x as a pivot, the cutting edges 14, or one of them, will force the wire against one of the cutting edges of the notch 8, and thus effect shearing.

45 When two wires are to be spliced, the stationary and loose wires are positioned in the crotch of the claw, the stationary wire is caused to enter the slot 15, and the loose wire to pass through the eye of the keyhole slot 12, and upon a circular motion being imparted to the implement 4, positive twisting together of the two wires will be effected.

50 The improvements herein defined while simple in character will be found thoroughly efficient for the purposes designed, and will result in the presentation of a highly durable and useful farm implement.

I claim:—

55 1. The combination with a hammer head having its poll provided with alined seats

{110

one of which is furnished with oppositely-inclined cutting edges, and with a laterally-projecting stud, of a member having a head provided in its interior with a key-hole shaped slot to engage with the stud and in its periphery with a notch having cutting edges and adapted to register with one of the seats in the poll.

2. A hammer head having its poll extended beyond its eyes to provide a pair of flanges, each having a seat, one of which is provided with oppositely inclined cutting edges, a laterally projecting stud carried by

the poll, and a member having a head provided in its interior with a key-hole shaped slot to engage the stud and in its periphery with a notch having oppositely inclined cutting edges to coact with the like edges of the seat of the flange. 15

In testimony that I claim the foregoing 20 as my own, I have hereto affixed my signature in the presence of two witnesses.

WILLIAM S. GUINTER.
